United States Patent Office

Des. 184,996
Patented Apr. 28, 1959

184,996

COMBINED DESK AND TELEVISION UNIT

Jacob Goldstein and Robert E. Donald, New York, N.Y.,
assignors to American Seating Company, Grand Rapids,
Mich., a corporation of New Jersey

Application August 29, 1958, Serial No. 52,451

Term of patent 14 years

(Cl. D33—11)

Figure 1 is a front and side perspective view of a combined desk and television unit, showing our new design.

Figure 2 is a similar perspective view of the desk showing the other side thereof.

The back and top of the unit are plain and unornamented.

We claim:

The ornamental design for a combined desk and television unit, substantially as shown and described.
